Patented Dec. 21, 1926.

UNITED STATES PATENT OFFICE.

TRIMBLE HALCOMB, OF INDIANAPOLIS, INDIANA.

BOLT AND RIVET CATCHER.

Application filed November 12, 1925. Serial No. 68,622.

This invention relates to safety devices especially adapted for use on rivet cutting devices.

Briefly stated, an important object of this invention is to provide a safety attachment for rivet cutting hammers having a reticulated guard which extends over the head of the rivet and prevents the same from flying through space when severed and which at the same time allows the operator to view the cutting operation and keep the chisel in position to engage the rivet on each cutting stroke.

A further and equally important object of the invention is to provide a safety attachment of the character specified having simple means whereby the same may be easily applied to a standard air hammer without the exercise of unusual skill or substantially altering the construction of the hammer.

Other objects and advantages of the invention will be apparent during the course of the following description.

In the accompanying drawing, forming a part of this application and in which like numerals are employed to designate like parts throughout the same,

Figure 1 is a perspective of the improved safety attachment in use;

Figure 2 is a group perspective of the guard and a screen which may be employed in connection therewith;

Figure 3 is a transverse sectional view of the improved guard with the screen attached.

In the drawing, the numeral 5 designates the shank of the improved guard, which shank is formed from a length of spring steel the intermediate portion of which is bent into circular formation to define a ring 6 to which a plurality of approximately parallel guard strips 7 may be welded or otherwise secured. The circular portion 6 and the guard strips 7 define what might be said to be a reticulated head adapted to be positioned over the head of a rivet to prevent the rivet head from flying through the air and causing damage when severed. It is believed to be obvious that when the chisel 9 of the hammer completes the severing operation the head of the rivet is likely to be thrown into the air with considerable force and possibly injure persons within a range.

The length of spring steel from which the frame of the guard is formed is looped to

define an attaching ring 12 adapted to extend about the forward portion of the air hammer 14. Figure 1 clearly illustrates that the terminal portions of the length of metal from which the frame is formed are coiled in opposite directions to define attaching and holding spring members 16 which yieldingly grip the intermediate portion of the hammer so as to hold the guard firmly in place. It is believed to be obvious that when the members 12 and 16 are encircled about the air hammer and are in reasonably firm engagement therewith the reticulated head will be positioned at the forward portion of the chisel. However, as the shank is of a spring metal the guard may be moved to one side in case the job of cutting the rivet heads is in close quarters.

Figure 2 illustrates that a supplemental screen 22 may be applied to the reticulated head and secured in place by spring clips 24. The screen 22 is employed in connection with small rivet heads, chippings and the like. However, the addition of the screen 22 does not materially obstruct the operator's view of the work in hand as the mesh is sufficiently open to allow for this and at the same time prevent the chippings and small rivet heads from flying substantial distances. It will be seen that the screen is backed up by the parallel strips 7 of the guard head and is reinforced thereby.

As previously stated a rivet and bolt head catcher constructed in accordance with this invention may be easily applied to an air hammer without the employment of bolts or other separate devices and when in place will effectively protect those near a particular job from injury.

The attaching rings 12 and 16 hold the reticulated head in place over the rivet being cut and as the shank is flexible the reticulated head may be raised up from the cutting end of the cutting tool. Also the head may be moved laterally and when released will promptly return to normal position at the end of the chisel.

It is especially important for the operator to be able to observe the progress of the cutting operation as the vibration incident to the cutting operation would in many cases cause the hammer to move laterally so that the chisel will no longer engage the rivet. If the hammer is operated with the chisel not in a position to engage the rivet the

chisel may be driven out of the hammer and possibly cause injury to someone or to objects within range.

Having thus described the invention what I claim is:—

1. A rivet shield for cutting tools comprising a shank adapted to be extended substantially parallel to the axis of a hammer and having an offset rear portion provided with 10 separate expansible attaching coils adapted to receive and engage the cutting tool, said attaching coils being an integral part of said offset rear portion and a head on the forward portion of the shank.
15. 2. A rivet and bolt head catcher for air hammers comprising a length of spring metal having its intermediate portion bent into circular formation and having its terminal portions coiled in opposite directions to 20 define attaching springs adapted to grip the barrel of a riveting hammer, and guard strips connected to the circular intermediate portion of the length of spring metal, said guard strips being spaced whereby to afford 25 a view of the cutting operation.
30. 3. A rivet and bolt head catcher for air hammers comprising a length of spring metal having its intermediate portion bent into circular formation and having its terminal portions coiled in opposite directions to 35 define attaching springs adapted to grip the barrel of a riveting hammer, and guard strips connected to the circular intermediate portion of the length of spring metal, said guard strips being spaced whereby to afford a view of the cutting operation, said length of spring metal being provided between said attaching springs and said circularly formed portion with a loop adapted to receive the

forward portion of the barrel of the riveting hammer.

4. A rivet and bolt head catcher for riveting hammers comprising a single length of metal having its intermediate portion bent to form a frame, the terminal portions of 45 said length of metal being coiled to provide separate attaching members adapted to detachably grip the barrel of a riveting hammer, said length of metal being provided between said attaching members and said frame with a loop to receive the barrel of the hammer, and a screen having means whereby the same may be detachably connected to said frame.

5. A rivet and bolt head catcher comprising a shank of spring metal adapted to be extended substantially parallel to the axis of a cutting tool and having the rear portion thereof provided with separate spaced attaching loops adapted to grip the barrel of 60 a cutting tool, and a head at the forward portion of said spring shank and having a plurality of spaced guard strips.

6. A safety attachment for use on rivet cutting tools comprising a shank adapted to be extended substantially parallel to the axis of the cutting tool and having means whereby the same may be secured thereto, a head secured to the forward portion of the shank and having spaced guard strips, and a separate screen having spring strips adapted to extend over and detachably engage said head to detachably secure the screen at one side of the guard strips whereby the screen will arrest the movement of small chips.

In testimony whereof I affix my signature:

TRIMBLE HALCOMB.
